UNITED STATES PATENT OFFICE.

PIERRE O. KEILHOLTZ, OF BALTIMORE, MARYLAND.

METHOD OF REGULATING BOILER-PRESSURE.

1,160,514.

Specification of Letters Patent. Patented Nov. 16, 1915.

Application filed August 6, 1914. Serial No. 855,425.

To all whom it may concern:

Be it known that I, PIERRE O. KEILHOLTZ, a citizen of the United States of America, residing in the city of Baltimore, State of Maryland, have invented certain new and useful Improvements in Methods of Regulating Boiler-Pressure, of which the following is a specification.

This invention relates to a method of controlling the pressure of steam boilers and generators. Such regulation has in the past been found imperfect because there is a considerable lag incident to its operation. The period of time which elapses between the change of draft and the building up of the fire to the temperature requisite to give the desired boiler pressure is an element, but more important than this is the lapse of time between the increase of the furnace temperature to this point and the increase of boiler pressure to normal or the point of regulation. The effect of the lag made up of both these elements is hunting of the regulator or a continued fluctuation of the boiler pressure above and below the normal pressure, or point of regulation. When the regulator owing to a drop in the boiler pressure due to increased load and steam consumption within the capacity of the furnace, acts to increase the draft, a considerable period of time elapses before the pressure of the boiler reaches the point of regulation. As the increased draft is continued through this period, the temperature of the furnace continues to increase until it becomes higher than is necessary to supply the demand and maintain the pressure for which the regulation is set, so that the boiler pressure mounts above the point of regulation and the regulator acts in the opposite phase, the fire being then cooled so that the boiler pressure drops to and below normal and the regulator must again act to increase the fire and the boiler pressure. This is the hunting difficulty as it has been encountered in the various attempts at regulation, and the object of the present invention is to evolve a method for controlling a steam generator, which shall not be subject to this defect.

The steam plant to which my method has been applied includes a compressor or blower, or rather a battery of blowers by means of which a forced draft is established and the control operates through and in connection with the blowers, though it may be

otherwise applied within the scope of the invention and an automatic stoker may be operated with the blower and thus utilized as part of the control. In the present instance, the blowers are driven each by a separate electric motor, and one or any number of blowers or compressors may be utilized depending upon the capacity of the plant and of the individual blowers.

The method which is the subject of my invention consists in controlling the steam generator to maintain the desired steam pressure by varying the draft, or both the draft and fuel feed, and causing the draft pressure to react upon and control and check the action resulting from the variation in steam pressure. The apparatus by means of which it is carried out in the present instance consists of a regulator which operates in response to the boiler pressure to increase or decrease the draft, the regulator being in turn controlled by the reaction of the draft pressure so that it is returned to normal and thus discontinues the regulating operation as soon as the variation in draft thus produced reaches a point where it corresponds to the existing variation of boiler pressure from the point of regulation. In the form of the apparatus shown, there is a regulator actuated by the variation of the boiler pressure above and below normal, the same being connected to the draft creating elements to increase or decrease the draft to compensate for the decrease or increase of boiler pressure, the regulator which is controlled by the boiler pressure being in turn connected to a member which is actuated by the variation in draft pressure so that the regulator is stopped or returned to normal when the variation in draft pressure thus produced corresponds to the variation in boiler pressure and steam consumption.

The apparatus used in the practice of the method may be widely varied within the scope of my invention but in order that the nature and operation of the invention may be understood, a steam plant and control embodying an apparatus by means of which the method of the invention may be carried out are illustrated in the accompanying drawings, in which—

Figure 1 is a diagrammatic view of the steam plant and regulator; Fig. 2 is an elevation showing the regulator proper; Fig. 3 is an elevation taken at right angles to Fig. 2; and Fig. 4 is a detail view. Fig.

5 is a horizontal section taken just above the axis of the roller in Fig. 2 on the line 5, 5 of said figure.

Referring to the drawing by numerals, 5 each of which is used to indicate the same or similar parts in the different figures, the illustration includes a boiler furnace 1 and blowers 2 delivering air under pressure beneath the grate by means of delivery pipe 3. The blowers may be of any desired 10 number; in the present instance, there are six, each being driven from a suitable source of power, for which purpose I have illustrated an individual motor 4 in connection with each blower. Preferably there 15 is also an automatic stoker 6, the stoker being driven from or connected to the corresponding blower as by a belt 6'.

The regulator consists of a diaphragm 5 to which the boiler pressure is communicated by means of a pipe 7. The diaphragm carries an upwardly disposed knife edge or equivalent element 8 which acts upon a horizontal lever or regulating member 9 pivoted at 10. The lever 9 carries a weight 11 which is adjustable toward and from the pivot and a suspended weight 12 which preferably consists of a plurality of small weights 13 so that the amount of the 20 weight may be changed to conform to the desired pressure or other variable quantities, the weight being used to counterbalance the steam pressure on the diaphragm. When the upward pressure on the diaphragm decreases below normal or the 25 point of regulation, the weights tend to swing the lever downward, and when it increases above normal, the long arm moves upward. The lever or regulating member 9 also carries an inverted bell jar 14, in this 30 instance pivotally connected at 15 to the outer end of the lever, the inverted bell jar 14 being inclosed within an upright jar 16, the jar being partially filled with water to a 35 level which will be assumed at the height of the broken line 17, the space in the inverted bell 14 above the liquid level being connected by means of a pipe 18 to the throat or delivery pipe of the blower or 40 draft creating element at 19. To give the necessary control of the blowers, the lever 9 is connected by means of a rod 20 including a link 21, to a second horizontal lever 22 which in turn is pivotally connected to 45 the swinging end 23 of a bell crank lever 24 mounted on a stationary pivot 25, and the lever 22 is connected by means of a rod 26 to a pilot valve 27 which controls the 50 flow to and from the fluid pressure cylinder 28. The valve 27 which is a commercial article and need not be specifically described, has two connections, one to the pressure pipe 29 and one to the outlet or relief pipe 30 respectively, and two ports 55 connected to the upper and lower ends of

the hydraulic cylinder 28. As the lever 9 swings up, actuated by the raising of the diaphragm 5 due to the increase of boiler pressure, the rod 26 being likewise moved upward, causes the fluid, usually water under pressure, to enter the lower end of the cylinder 28, the upper end of the cylinder being exhausted through relief pipe 30 and under these circumstances, the piston 31 moves upward. The reverse action of the 75 diaphragm due to decrease in boiler pressure below normal, causes the piston to move downward.

The piston 31 carries an upright rod 32 with the toothed rack 33. This rack meshes 80 with the teeth of a gear 34 on the shaft 35 carrying cams 36 which engage rollers 37 carried by lever arms 38 which when electrically driven blowers are used, may be connected to the switches 39. In the 85 form of the invention shown, each of the switches 39 when closed, serves to cut out a block of resistance in series with the motors so that when the switch is in, the motor speed and resulting draft, and if so connected, the fuel feed, are definitely increased, and when the switch is out, the motor speed and draft, etc., dependent 90 thereon, are reduced.

A diagram of a circuit for controlling 95 the speed of the motors is shown in connection with Fig. 4. In this figure I have shown positive and negative buses *b* and *c* and motors 4, 4 with the armatures connected across the buses and the fields *F* on 100 a shunt containing a series of resistance coils *R*. In connection with each resistance unit *R*, there is a switch with contacts *d*—*f* by which the corresponding resistance unit may be short circuited. Each switch is actuated by a coil *G* controlled by a corresponding cam-controlled switch 39 of the series already described. The manner of 105 operation is apparent. As contact is made at each of the series of switches 39 the corresponding magnet *G* is energized, the switch *d*—*f* is closed, the corresponding resistance *R* is cut out, and the speed of the 110 motors increased. The reverse is true for the opposite regulation.

In order that there may be a proper check upon the action of the hydraulic cylinder, for unless some means were provided for stopping it, the rack would first move upward for the full stroke of the piston, or 115 until reverse regulation takes place, and then downward for a similar stroke, a wedge 40 is provided. This is suspended from the piston rod and acts on the follower 41 on the depending end of the bell crank lever 24, the same being held against the wedge by a spring 41', which is compressed between the yoke 41² and the lever arm 24. When the regulator acts in response to the increased boiler pressure with 120 125 130

the rod 32 moving upward, the wedge 40 likewise moving upward in the guide 40', engages the follower 41 and swings the bell crank right handed about its center moving 5 the pivot 23 of the lever 22 downward, whereby the valve 27 is closed and the motion of the piston arrested until there is a further action of the regulator giving a step by step action of the regulator until the 10 boiler pressure responds.

The device thus described serves effectually to increase the draft created by the blowers when the boiler pressure drops below a given point of regulation, and likewise to decrease the draft when the boiler pressure mounts above the same point, but owing to the time element which is always present, *i. e.*, the lag of the furnace temperature as compared to the draft, and 15 boiler pressure as compared to the furnace temperature, the regulation thus attained is not sufficiently accurate, and the regulator hunts with the usual resulting waste of fuel and loss of boiler pressure. To overcome this difficulty and give the apparatus the desired degree of accuracy, I have added the compensating element referred to. In the operation of this feature, the draft pressure is immediately communicated to the 20 bell jar 14 in the form of air pressure, and has an appreciable effect in supporting the weights on the long arm of the lever 9 which tend to swing that lever downward against the pressure communicated from the boiler 25 to the diaphragm 5. Now the downward motion of the long arm of the lever 9, produces the regulative effect whereby the boiler pressure is decreased and the upward motion produces the opposite effect so 30 that if the pressure of the boiler has risen above normal, the regulation which takes place to overcome this variation is as follows: The draft, and fuel feed if so connected, having been decreased by upward 35 motion of the long arm of the lever 9 caused by upward pressure on the diaphragm 5, the weights 11 and 12 being partially supported by the draft pressure communicated to the bell jar 14, the regulating effect produced on the draft being immediately communicated to the bell jar, reduces the air pressure therein and causes the lever 9 to drop correspondingly so that the regulating 40 action, (referring to the draft and fuel feed 45 variation or either), terminates, for the time being, to be continued or repeated if the boiler pressure is sufficiently in excess of the normal to again raise the lever 9 with the supporting effect of the bell jar 14 thus 50 reduced.

It will be noted that the change in fuel and air supply is proportionate or substantially proportionate to the variations in steam consumption being compensated. For 55 instance, if there is a large increase in boiler

pressure, due to decreased load or increased furnace temperature the lever 9 is moved well upward and a correspondingly great reduction of the pressure within the jar 14 and a consequent reduction of blower 70 pressure and fuel feed, if the feed is so connected, is necessary to return the lever 9 to its normal position, thus terminating the regulating effect, for with the lever 9 in this position, the circuits of the motors driving 75 the blowers are returned to normal condition so that the regulating operation or cycle is completed to be repeated in case the boiler pressure is not corrected and the variation remains sufficient to again raise the dia- 80 phragm and operate the regulating apparatus. Thus the operation consists in delivering to the furnace definite predetermined quantities of fuel and air, or air alone. It will also be apparent that with the regulator 85 thus controlled by means of draft pressure, hunting cannot take place for the first effect of the change in blower speed which results from the movement of the lever 9 in response to the change of position of the 90 diaphragm, is a change of draft pressure which is immediately communicated to the bell jar 14 and to the lever 9, the tendency to move the latter being opposed to the regulating impulse just imparted to it, so 95 that the parts being properly designed, the regulator is returned to normal long before the boiler pressure has responded to the regulating action, and hunting or fluctuation of the regulative element above and below 100 normal is forestalled and prevented.

I have thus described specifically and in detail my method of controlling the pressure of a steam boiler, and an apparatus by means of which the method may be accomplished. This has been done in order that the nature of the invention may be fully understood; however, the specific terms applied herein are used descriptively rather than in their limiting sense and the scope 110 of the invention is defined in the claims.

What I claim and desire to secure by Letters Patent is:

1. A method of operating a mechanical apparatus including a steam boiler, a furnace and a pressure regulator, to control the boiler pressure, the method consisting in supplying varying quantities of fuel and air to the furnace in response to the variations in steam pressure in the boiler and causing 115 the variation in air supply pressure to react directly upon the regulator determining the quantities of fuel and air, and preventing hunting of furnace conditions.

2. The method of controlling combustion 120 in the furnace of a steam generator having a regulator operated by the steam pressure to regulate combustion and hence controlling the steam pressure, which consists in supplying to the furnace definite amounts of 130

fuel and air and thus controlling the generation of steam in response to the load and steam pressure in the generator, and causing the pressure of the air supply to react directly upon the regulator independently of its action through the steam pressure.

3. A method of regulating the generation and pressure of steam in a steam plant including a furnace, a steam boiler and a regulator operated by steam pressure to control combustion by varying the generation of heat in the furnace which consists in supplying to the furnace air under pressure in excess of that of the atmosphere, varying the air supply pressure to compensate for variations of steam pressure and utilizing these same variations in air supply pressure to prevent hunting by having them re-act directly on the air supplying means as soon as that pressure varies by a pre-determined amount bringing the air supply pressure back substantially to the point from which regulation started.

4. A method of regulating the generation and pressure of steam in a steam plant including a furnace, a boiler and a pressure regulator by varying the generation of heat in the furnace which consists in supplying to the furnace air under pressure in excess of that of the atmosphere, varying the air supply pressure to compensate for variations of steam pressure and utilizing these same variations in air supply pressure to prevent hunting by causing them to re-act directly on the air supplying means causing the air supply pressure to approach the point from which regulation started as soon as that pressure varies by a pre-determined amount.

5. A method of operating a mechanical draft apparatus, including a steam pressure actuated draft regulator, to regulate combustion and hence steam pressure which consists first in varying the operation of the draft apparatus in response to fluctuations in the steam pressure, and second, in causing the variation in air supply pressure produced by the first step to react directly upon the regulator and return the draft apparatus to normal operating condition as soon as the air pressure is varied by a pre-determined amount, whereby hunting of furnace conditions is prevented.

6. A method of operating a mechanical draft apparatus including means for creating a forced draft, a motor to drive the same, a pressure regulator operated by variations in the steam pressure to control the speed of the motor and a device for checking the operation of the regulator in the form of a connection from the air supply to the regulator, the method consisting first, in regulating the motor by which forced draft is produced to compensate for variations in steam pressure, and second, in causing the variations in air supply pressure produced by the first step to re-act upon the motor and check the regulating action resulting from the variation in boiler pressure whereby excessive fluctuations of furnace conditions and steam pressure are prevented.

Signed by me at Baltimore, Maryland, this 4th day of August 1914.
